UNITED STATES PATENT OFFICE

2,547,792

FARM GATE

Floyd E. Speed, Oakfield, N. Y.

Application March 11, 1948, Serial No. 14,212

1 Claim. (Cl. 39—87)

1

The present invention relates to improvements in heavy duty farm gates of horizontally elongated types which range up to 16 feet in length and 53 inches in height, and the purpose of the invention is to so construct a gate that, notwithstanding these proportions, is strong, durable and relatively easy to install.

More specifically, the invention has to do with an elongated rectangular framework which is adapted to be covered with strong conventional fence wire W of a kind which can be readily purchased on the open market.

Another object of the invention is to provide a gate wherein the hinging and attaching knuckles are spaced inwardly from the top and bottom horizontal frame members, instead of being directly at the respective corners, there being an arrangement of frame stabilizing braces and the brace closest to the hinging knuckles being especially arranged so that the point of attachment at the upper end thereof is substantially in the immediate vicinity of the location of the adjacent upper hinge knuckle, thus transferring forces and equalizing stresses and strains.

The primary object of the invention is to provide a heavy farm gate of the type specified wherein the hinge knuckles have bushings, the bushing in the lower hinge knuckle being relatively long and slidably mounted, whereby to permit the new gate, when purchased, to be hung on existing types of hinging brackets without having to remove the brackets, this due to the adjustability of the long self-accommodating bushing in the lower hinging knuckle.

Other objects and advantages will become more readily apparent from the following description in the accompanying illustrative drawings.

In the drawings:

Figure 1 is a perspective view of a farm gate constructed in accordance with the principles of the present invention;

Figure 2 is a top plan view of the gate showing adjacent posts and the gate mounted for operation therebetween; and,

Figure 3 is an enlarged fragmentary sectional and elevational view taken on the plane of the line 3—3 of Figure 2, looking in the direction of the arrows.

Referring now to the drawings by distinguishing reference numerals, the main gate frame is denoted by the numeral 5 and is of elongated rectangular form and the frame members are seamless steel tubes or pipes, there being top and bottom horizontal members 6 and 7 and vertical or transverse end members 8 and 9. The meet-

ing ends of the frame members are suitably mitered and welded or otherwise connected securely together. In this type of a gate I provide reliable bracing means comprising vertical struts 10 and 11, the latter being situated between and connected to the intermediate portions of the top and bottom frame members 6 and 7. These struts are properly spaced in relation to the other frame members, particularly the end frame members 8 and 9 in order to equalize the distribution of forces and weight. There is a diagonal brace 12 provided, and this is situated between the struts or braces 10 and 11 and connected at its opposite ends to the upper and lower frame members 6 and 7. In addition, there is a second diagonal brace 13, and this is connected at its lower end as at 14 to the frame member 8 and connected as at 15 to the upper end portion of the vertical frame member 9. It will be observed that the point of connection 15 with the part 9 is inwardly of the corner joint 16. Also, the upper hinge knuckle 17 is rigidly secured to the member 9 and located downwardly from the corner 16. The hinge knuckle 17 is provided with a bushing 18.

Reference is had now to the lower hinge knuckle 19, and this is shown as connected upwardly from the lower corner 20. The main feature here is that the bushing 21 in the knuckle is elongated and in practice will perhaps be some 14 inches in length. This bushing 21 is freely slidable in the knuckle 19. Because of this adjustable hinge feature the upper stationary hinge knuckle and stationary bushing 18 may be connected with the hinge pin 22 of the hinge bracket 23 and the bushing 21 connected with the hinge pin 24 of the lower hinge bracket 25 on the gate post 26. The bushing 21 will shift and slide in the knuckle to accommodate whatever position is had by the bracket 25 on the post 26. In most cases with this gate, the purchaser can take his old gate (not shown) off and slip on this improved gate, using the same hinges, that is, the conventional L-shaped type as seen in the drawings, for the purposes. The distance between the hinge brackets is not too important because the adjustable bushing 21 compensates for any variation. Also, the improved hinge arrangement permits new hinge brackets or fixtures to be attached to the post without having to measure the distance between same too closely to fit precisely the types of hinge knuckles which are on ordinary gates. This variation in the distance between hinge brackets is allowed because of the presence of the slidable bushing in the knuckle 19.

The improvements reside in spacing the knuckles 17 and 19 inwardly from the corners 16 and 20 of the hinging end of the gate to balance the hinged end of the gate and combining therewith a brace 13 which has its left-hand end 15 attached to the frame member 9 so that it coincides with the upper hinge knuckle 17. As stated the principal novelty resides in having the bushing 21 slide in the knuckle 19 and using a bushing which is sufficiently long to permit it to accommodate hinge brackets which are placed varying distances apart on the post.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

The numeral 27 designates an eye carried by the free swingable end portion of the gate and which is adapted to accommodate a guy wire, not shown, if same is needed by the farmer. Some farmers use the guy wires to distribute stress to prevent gate sagging.

The letter W designates the wire covering on the gate.

Having described the invention, what is claimed as new is:

A farm gate of the class described comprising a horizontally elongated rectangular frame embodying spaced parallel upper and lower horizontal frame members and vertical end members

connecting said upper and lower members, a pair of vertically disposed bracing struts rigidly interposed between the central portions of said upper and lower frame members, a diagonal brace located and secured between said upper and lower frame members and situated in the space existing between the vertical struts, and a second diagonal brace connected at its lower end with the lower frame member adjacent to one of said vertical bracing struts, the upper end thereof connected with the adjacent end member at a point spaced downwardly from the adjacent upper corner of said frame, and upper and lower hinge knuckles mounted on said last named end member, one, the upper hinge knuckle, being secured to said end member at a point diametrically opposite to the upper end of said second-named diagonal brace, the remaining, the lower hinge knuckle, also secured to said end member, being provided with a bushing, said bushing being comparatively long and being freely slideable in said last-named knuckle for self-adapting connection with a fixed hinge pintle on a stationary gate supporting post.
